UNITED STATES PATENT OFFICE.

CHRISTOPHER DRESSER, OF LONDON, ENGLAND, ASSIGNOR TO WILSON & FENIMORES, OF PHILADELPHIA, PENNSYLVANIA.

DESIGN FOR WALL-PAPER.

Specification forming part of Design No. 9,978, dated May 15, 1877; application filed March 17, 1877.
[Term of Patent 3½ years.]

To all whom it may concern:

Be it known that I, CHRISTOPHER DRESSER, of London, England, have originated and designed a Pattern for Wall and other Papers, of which I hereby declare the following to be a specification:

The nature of my design is fully shown in the accompanying photographic illustration, which forms a part of this specification.

My design consists, substantially, of a plain ground, A, covered in regular spacing with oval figures, consisting of two embracing grotesque lily-leaves, B, inclosing a fleur-de-lis-like spray of geometric flowers, C.

What I claim as my invention, and desire

to secure by Letters Patent of the United States, is—

The design for a wall-paper, consisting of a plain ground, A, covered with oval figures, composed of lily-leaves B, which inclose sprays of flowers C, substantially as shown and described.

In testimony that I claim as my invention the design hereinbefore described I have hereunto signed my name in the presence of two subscribing witnesses.

CHRISTOPHER DRESSER.
